US00D360157S

United States Patent [19]

Sandell et al.

[11] Patent Number: Des. 360,157

[45] Date of Patent: ** Jul. 11, 1995

[54] SENSOR HEAD FOR PASSIVE INFRARED MOTION DETECTOR

[75] Inventors: **Donald R. Sandell**, San Jose; **Gary Bordenkircher**, Livermore, both of Calif.

[73] Assignee: **Inteletron Products Company**, Hayward, Calif.

[**] Term: **14 Years**

[21] Appl. No.: **22,851**

[22] Filed: **May 13, 1994**

[52] U.S. Cl. **D10/106**

[58] Field of Search D10/104, 106, 116, 121; 340/521, 540, 555, 556, 557, 565, 571, 600, 628, 629; D26/28

CLAIM

The ornamental design for a sensor head for a passive infrared motion detector, as shown and described.

DESCRIPTION

FIG. 1 is a perspective view of a sensor head for a passive infrared motion detector showing our new design;

FIG. 2 is a front elevational view thereof;

FIG. 3 is a right elevational view thereof; the left elevational view is a mirror image;

FIG. 4 is a rear elevational view thereof;

FIG. 5 is a top plan view thereof; and,

FIG. 6 is a bottom plan view thereof.

FIG. 2

FIG. 5

FIG. 1

FIG. 4

FIG. 6

FIG. 3
